Primary Examiner—Robert C. Spangler
Attorney, Agent, or Firm—Charles J. Fickey

[57] **CLAIM**

The ornamental design for a combined dispensing container and cap, substantially as shown and described.

DESCRIPTION

FIG. 1 is a top plan view of a combined dispensing container and cap showing our new design;
FIG. 2 is a front elevational view thereof;
FIG. 3 is an elevational view looking from the right side, the left side being the same as the right side;
FIG. 4 is a back elevational view; and
FIG. 5 is a bottom plan view thereof.
